UNITED STATES PATENT OFFICE

ALEXANDER WILLIAM STEWART, OF GLASGOW, SCOTLAND

AIR CIRCULATING APPARATUS

Application filed April 2, 1931, Serial No. 527,094, and in Great Britain June 12, 1930.

This invention relates to apparatus devised to effect circulation of the air in rooms or compartments, such as saloons, smoke-rooms and the like.

5 Cabin, desk, and ceiling fans as heretofore commonly used for the purpose are open to the objection that they deliver air in one direction only, or, if they perform gyroscopic movements, more or less complicated 10 mechanism is required for effecting the desired movements.

The apparatus according to the invention is a self-contained ductless unit comprising a casing which houses a motor-driven fan 15 and which is provided with a directional air nozzle or nozzles for discharging the air impelled by said fan.

The casing of the apparatus may be constructed as the base of a table lamp of which 20 the lamp bulb may be in series with the motor for driving the fan.

There may be arranged within the casing a heat-exchanger such as an electric heater, or a cooler of suitable type.

25 Air humidifying means comprising a water reservoir beneath which is arranged an electric water-heating unit may be provided within the casing.

Several embodiments of apparatus constructed in accordance with the invention are 30 illustrated in the accompanying drawings, Fig. 1 being a vertical section showing a table fan embodiment, Fig. 2 a part elevation part vertical section of a second table fan embodiment, Fig. 3 a vertical section of a third table fan embodiment, incorporating a cooler, Fig. 4 an elevation of the embodiment shown in Fig. 3 drawn to a smaller scale, Figs. 5, 6 and 7, a vertical section, a horizontal section on the line 6-6 of Fig. 5, and an elevation drawn to a smaller scale, respectively, of a fourth table fan embodiment incorporating a heater and an air humidifier, and Figs. 8 and 9, a vertical section and a 45 sectional plan on the line 9-9 of Fig. 8, respectively, of a ceiling fitting.

Similar reference numerals denote similar parts in the several views.

The apparatus shown in Fig. 1 comprises a 50 metallic casing 1, which houses a motor-

driven fan impeller 2, having an air inlet 3 at the underside of the casing 1 and having a plurality of air outlets distributed around the periphery of the casing 1 and presented by a row of directional air nozzles 55 or louvres 4.

The nozzles 4 are individually controllable so that each of the sitters at a table 5 on which the apparatus rests can adjust the nozzle 4 discharging an air stream in his direction, to vary the path of air and the volume discharged.

The air inlet 3 is defined by a convergent shell 6 fitted within the underside of the casing 1.

The base portion of the casing 1 is cylindrical while the upper part of the casing is conoidal with flats to take the flanges 7 of sockets 8 for the nozzles 4.

9 denotes the fan motor which is surrounded by a dome 10.

In the construction shown in Fig. 2 the casing is composed of panels 1', 1'' and forms the base of a table lamp whose standard is indicated at 11.

Sockets 8' for the nozzles 4 are fitted to the panels 1''.

In the construction shown in Figs. 3 and 4 air entering the casing 1³ at 12 traverses passages 13 formed between the casing and an ice box 14 within the casing, before entering the inlet 15 to the fan impeller 2. As will be understood, when the air current is to be cooled, the box 14 is filled with ice. The lower part of the casing 1³ is lined with sheet 85 metal 16 to form a watertight drain receptacle for collection of water condensing on the exterior walls of the box 14. The fan motor 9 is sustained from the upper portion of the casing 1³ which, together with the 90 nozzle housing 1⁴, is detachable from the lower half of the casing 1³ to permit access to the ice box 14.

In the construction shown in Figs. 5-7 air entering the air inlet 3 on the underside of the casing 1⁵ traverses an electric heating unit 17 and air humidifying means comprising a water reservoir 18 on the underside of which is arranged an electric water-heating unit 19 housed within a metallic shell 20. 100

21, 22 denote air spaces within the shell 20 and beneath the heating unit 19, said spaces being separated by an asbestos washer 23 on each side of which is arranged an asbestos distance piece 24. The water reservoir is traversed by wash plates 25 along the bottom edges of which are formed holes 26. The apparatus is equipped with feet 27 adapted to rest on a table top or the like.

10 The construction shown in Figs. 8 and 9, which is a ceiling fitting, includes electric heating elements 28, 28' and resistance elements 29, 29', on the outlet side of the fan impeller 2, which latter is driven by a pair 15 of coupled motors 9, 9' protected from the heating elements 28, 28' by asbestos faced walls 30. The resistance elements 29, 29' are included in the speed regulating circuit for the motors 9, 9' and also serve as supplementary air-heating means.

20 What I claim is:—

1. Air circulating apparatus comprising a casing having an air inlet and presenting on its lateral wall a set of sockets, a motor 25 driven fan housed within said casing, and directional nozzles each constituting an air outlet, said nozzles being mounted for universal movement in said sockets, permitting discharge of air in any desired direction 30 within the range of a hemisphere.

2. Air circulating apparatus according to claim 1 and including heat-exchanging means fitted within the casing.

3. Air circulating apparatus according to 35 claim 1 and including air humidifying means fitted within the casing.

4. Air circulatng apparatus according to claim 1 and including a water reservoir on the inlet side of the fan and an electric water- 40 heating unit beneath said reservoir.

45 In testimony whereof I have signed my name to this specification.

ALEXANDER WILLIAM STEWART.
